(57) **CLAIM**

I claim the ornamental design for a banner apparatus for vehicle trailer hitch receiver, as shown and described.

DESCRIPTION

FIG. 1 is a perspective view of a banner apparatus for vehicle trailer hitch receiver, illustrating the invention displaying a tall banner, showing my new design;

FIG. 2 is a left-side elevational view of the invention, illustrating the invention displaying the tall banner;

FIG. 3 is a right-side elevational view of the invention, illustrating the invention displaying the tall banner;

FIG. 4 is a front elevational view of the invention;

FIG. 5 is a rear elevational view of the invention;

FIG. 6 is a top plan view of the invention;

FIG. 7 is a bottom plan view of the invention; and,

FIG. 8 is a right-side elevational view of the invention, in an alternate position of use illustrating the invention displaying a short banner.

The broken lines showing a vehicle in FIG. 1 and a banner in FIGS. 1, 2, 3, and 8 are included for the purpose of illustrating the invention in use and form no part of the claimed design.
